Ward, Crosby & Smith

UNITED STATES PATENT OFFICE.

ROBERT Y. BARROWS, OF RUTHERFORD, NEW JERSEY, ASSIGNOR TO ROBERT Y. BARROWS, INC., A CORPORATION OF NEW YORK.

RECEPTACLE.

Application filed April 20, 1922. Serial No. 555,753.

To all whom it may concern:

Be it known that I, ROBERT Y. BARROWS, a citizen of the United States, and resident of Rutherford, State of New Jersey, have 5 invented certain new and useful Improvements in Receptacles, of which the following is a specification.

My invention relates to improvements in receptacles and more particularly to an improved arrangement for dispensing substances from receptacles whereby limited quantities of substances from receptacles may be discharged therefrom in a more desirable and efficient manner. Further and 15 more specific objects, features and advantages will more clearly appear from the detail description given below taken in connection with the accompanying drawings which form a part of this specification. In 20 the drawings, Fig. 1 is a vertical view partly in section of a toilet powder receptacle or can embodying my invention in a preferred form thereof. Fig. 2 is a bottom or inside view of the cover of the receptacle, removed, and showing the parts located therein. Fig. 3 is a view similar to Fig. 1 but showing a modified arrangement. Fig. 4 is a vertical detailed section showing still another modification. Fig. 5 is a bottom view 25 of parts shown in Fig. 4. Fig. 6 is a perspective illustrating a modification of the valve member shown in Fig. 4. Fig. 7 is a view similar to Fig. 4 illustrating a further modification. Fig. 8 is a bottom view 30 of parts shown in Fig. 7, partly in section. Fig. 9 is a perspective of the valve member shown in Fig. 7.

Referring to Figs. 1 and 2, 1 represents a suitable receptacle in the form of a can 40 provided with a cover member 2, having a discharge opening 3 in the top thereof adapted to be closed by a rubber valve member 4 which seats on the outside thereof. Connected to and passing through the rubber 45 valve member 4 is a pin or spindle 5 to the lower end of which is attached a weight 6. The pin 5 passes freely through a hole in a leaf spring 7 which leaf spring bears downwardly on the weight 7 and is provided with up-turned ends at 8 which bear against the 50 inside of the cover member 2 so that the spring serves as resilient means acting on the valve 4 and its connected parts to tend to hold the valve to close the discharge 55 opening 3.

When the receptacle is shaken particularly in line with the spindle 5, the inertia of the valve 4 and its connected parts including the weight 6 is such as to overcome the action of spring 7 and cause the valve 60 4 to open discharge opening 3 and if the receptacle be inverted and shaken or reciprocated in line with the spindle 5, a limited amount of the substance obtained therein may be discharged through the discharge opening. When, however, the movement of the receptacle is arrested momentarily or otherwise, the spring 7 is sufficient 65 to close the valve 4 irrespective of the position of the receptacle. That is, the spring 70 7 is of sufficient strength to overcome the weight of the valve and its connected parts including the weight 6 when the receptacle is inverted. It will be noted that the spindle 5 extends within the receptacle and the 75 weight 6 and spring 7 are all conveniently situated within the receptacle in the cover member 2 and are easily assembled therein.

Referring to Fig. 3 I there show a receptacle 10 having a similar discharge opening at 11 in the cover thereof adapted to be closed by metal valve 12 having an integral spindle 13 extending within the receptacle. The spindle 13 is reduced at its lower end and over the reduced part, is 80 placed a weight 14 held thereon by a pin 15. The leaf spring 16 has its ends bearing on the inside of the cover of the receptacle and is apertured at its center to extend around the spindle 13 and bear upon the 85 upper side of the weight 14. The method of operation is the same as described in connection with Figs. 1 and 2.

Referring to Figs. 4 and 5 the receptacle 90 20 is there shown provided with a cover member 21 having a discharge opening at 22 adapted to be closed by a metal valve 23 on the outside of the opening. The valve 23 has an enlarged head and a central part 24 extending within the cover of the receptacle and provided with lateral ribs 25 which serve to guide the same in its reciprocal movement in the discharge opening 22. The same is also provided with stops 26 which limit the movement of the valve 95 member in an outward direction. Connected to the lower end of the valve member is one end of a coil tension spring 27, the lower end of the spring being connected 100 to a wire frame member 28 which extends 105 to a wire frame member 28 which extends 110

upwardly and the upper ends of which are partially coiled within the cover member as at 29. The spring 27 holds the frame member 28 in operative position within the cover member and at the same time tends to hold the valve 23 closed. Upon inverting and shaking the receptacle the inertia of the valve 23 is sufficient to overcome the spring 27 and open the valve momentarily in order 10 to discharge a limited amount of the material in the receptacle. The spring 27, however, is sufficient to overcome the weight of the valve 23 when the receptacle is stationary and irrespective of its position, so that normally the spring will maintain the valve closed.

In Fig. 6 I show a modified form of valve member for use in the arrangement shown in Figs. 4 and 5. The valve member 30 20 there indicated being enlarged at its lower portion as at 31 so as to provide additional weight in order to give additional inertia to the valve member when the receptacle is shaken.

Referring to Figs. 7, 8 and 9, 40 there represents the cover of a similar receptacle provided with a discharge opening at 41 adapted to be closed on the outside thereof by valve 42 having connected thereto a spindle 43 which extends within the receptacle and is provided with integral wings 44 adapted to guide the same in its reciprocal movement in the cover member. The valve member is also provided with an apertured lug 45 to which is connected one end of a coil tension spring 46, the other end of which is connected to the frame member 47 and 48. The frame member 47 has two upwardly extending arms, the ends of 40 which are bent outwardly as at 48' and situated within the head 49 in the cover member 40.

The arrangements shown are particularly 45 advantageous for dispensing talcum powder and similar substances, but may be used for dispensing any other materials including liquids, such as toilet wafers, etc.

While I have described my improvements in great detail and with respect to preferred 50 forms thereof, I do not desire to be limited to such details or forms since many changes and modifications may be made and the invention embodied in widely different forms without departing from the spirit and scope 55 thereof in its broader aspects.

What I claim as new and desire to secure by Letters Patent is:

1. A receptacle having a discharge opening, a valve normally closing said opening but adapted to open the same upon shaking the receptacle, and resilient means acting to hold said valve to close said opening irrespective of the position of the receptacle when the receptacle is stationary.

2. A receptacle having a discharge open-

ing and a valve normally closing said opening, a spring interposed between said receptacle and portion of said valve, said spring being adapted to normally hold said valve closed irrespective of the position of the 70 receptacle but adapted to permit the same to open momentarily upon shaking the receptacle.

3. A receptacle having a discharge opening, a valve for closing said opening and a 75 spring for normally holding said valve to close said opening, the inertia of said valve being such that when the receptacle is shaken it overcomes said spring and momentarily opens the opening, and the spring 80 being of sufficient strength to cause the valve to close the opening when the receptacle is stationary and irrespective of the position thereof.

4. A receptacle having a discharge opening, a valve extending through said opening and adapted to close the same by seating on the outside thereof, and spring means 85 for normally holding said valve so as to close said opening irrespective of the position of the receptacle, said means being adapted to permit said valve to open momentarily upon shaking the receptacle.

5. A receptacle having a discharge opening and a valve normally closing said opening, said valve comprising a weighted head and a cylindrical stem, and means formed on said stem for connecting a spring member thereto, the inertia of said valve being such as to cause a momentary opening of 100 said valve against the resistance of said spring member upon shaking the receptacle.

6. A receptacle having a discharge opening, a valve for closing the opening, resilient means tending to hold said valve to close said opening, the inertia of said valve and connected parts, when the receptacle is shaken, being sufficient to overcome the resilient means and cause the valve to open 105 the opening, and the resilient means acting to overcome the weight of the valve and connected parts to close the valve when the receptacle is stationary and irrespective of its position.

7. A receptacle having a discharge opening, a valve for closing said opening and a leaf spring in the receptacle tending to hold said valve in closed position, the inertia of said valve and connected parts, when the receptacle is shaken being sufficient to overcome the spring and cause the valve to open, and the spring acting to close the valve when the receptacle is stationary irrespective of its position.

8. A receptacle having a discharge opening, a rubber valve adapted to close the opening by seating on the outside thereof, said valve having parts extending within the receptacle, a leaf spring within the receptacle and acting on said parts to normally 125 close the opening.

hold the valve closed; the inertia of said valve and connected parts, when the receptacle is shaken being sufficient to overcome the spring and cause the valve to open, and 5 the spring acting to close the valve when the receptacle is stationary irrespective of its position.

9. A receptacle having a discharge opening, a valve adapted to close the opening by 10 seating on the outside thereof, said valve having parts extending within the receptacle, a spring within the receptacle and acting on said parts to normally hold the valve closed, the inertia of said valve and 15 connected parts, when the receptacle is shaken being sufficient to overcome the spring and cause the valve to open, and the

spring acting to close the valve when the receptacle is stationary irrespective of its position.

20

10. A receptacle having a discharge opening, a valve adapted to close said opening by seating on the outside thereof, a spindle connected to said valve and extending within the receptacle, a weight connected 25 to said spindle and a leaf spring urging said weight and valve in a direction to close said opening and normally closing said opening irrespective of the position of the receptacle but adapted to open the same 30 momentarily upon shaking the receptacle.

In testimony whereof I have signed my name to this specification.

ROBERT Y. BARROWS.
